UNITED STATES PATENT OFFICE.

JAMES N. McCONNELL, OF UPPER SANDUSKY, OHIO.

BURIAL CASKET.

Application filed March 25, 1926. Serial No. 97,379.

This invention relates to improvements in burial caskets or couches, and has for its principal object the provision of a casket or couch formed with novel features by which the interior of the casket or couch when on display is adequately and tastefully illuminated so as to clearly disclose the contents thereof.

Another object of the invention resides in the provision of a burial casket or couch wherein the illuminating devices are mounted upon a swinging supporting frame carried in connection with the lid or cover section of the casket, the object in view being to permit of the adjustment of said frame so that the latter will assume positions governing directly the degree of illumination which said devices are capable of casting upon the interior of the casket, whereby a control is provided to modulate the intensity of the light, when desired, to produce more artistic and beautiful effects.

For a further understanding of the invention reference is to be had to the following description and accompanying drawings wherein:

Figure 1 is a front elevation of a burial casket or couch provided with the improved illuminating means comprising the present invention, the cover section of the casket being shown in an elevated position,

Figure 2 is a vertical transverse sectional view taken through the couch or casket on the plane indicated by the line 2—2 of Figure 1, there being shown in dotted lines one of the adjusted positions of the illuminating devices.

In accordance with the present invention there is provided a burial casket 1 which, as it will be understood, may be formed from any desired materials or in any one of the many different designs in which articles of this kind are made. At present, the casket is in the form of a "full couch", although it may be in the form of a "semi-couch", if desired, without departing from the principles of the invention. As shown, the casket consists of a body section 2, which is constructed to include vertical side and end walls 3 and a bottom 4. Hinged to the upper rear edge of the body section is a lid or cover section 5, capable of being swung to assume an open position, as shown in Figure 2, to render the interior of the body section accessible. The sections 2 and 5 are of course suitably decorated and finished in

any desired manner to present a pleasing appearance. The cover section in this instance is formed with a swinging lid 6, as shown in Figure 2, and likewise the body section is provided, along the front wall thereof, with a hinged panel 7, which may be raised or lowered as desired. When these parts are positioned as indicated in Figure 2, the casket is open for convenient and adequate display, permitting of the placing of flowers, and other funeral emblems and decorations on and around the casket to enhance its appearance.

In accordance with the present invention the cover section 5 is provided with a support 8 which is pivoted as at 9 upon said cover section so as to be capable of swinging through an arc of substantially ninety degrees. This support is adapted to carry fittings 10 for the reception of electric incandescent lamps 11. The pivotal connections 12, between the support 8 and the cover section 5 includes springs 13 which exercise a pressure on said support to maintain the latter stationary in any one of its adjusted positions throughout its entire arc of swinging movement.

It will be seen by reference to Figure 2 that when the support occupies a full line position shown in this figure, the lamps 11 will be positioned directly over the body section 2 so as to provide maximum illumination for said body section and also the lid 6. If it is desired to diminish this maximum degree of illumination the support is swung downwardly, thereby removing the illuminating elements from the zone of the body section and reducing the degree of illumination of the body section. The body section is preferably provided with ordinary dry batteries 14 which are employed to energize the lamps 11, although ordinary house current may be employed for this purpose when available.

In view of the foregoing it will be seen that the present invention provides a means for illuminating a casket by which the contents of the latter may be artistically and attractively illuminated without offending the ethics of good taste under circumstances where the invention is employed. By the provision of the swinging support therefor, the illumination which the lamps give may be varied and controlled to suit the peculiar requirements of each particular display.

What is claimed is:

1. In a burial casket, a body section, a

- cover section hinged to said body section and formed to include an open sided frame structure, a lid hinged along its lower edge to said frame structure, a support pivotally mounted within said frame structure, an incandescent lamp carried by said support, and means operating to maintain said support in adjusted positions relative to said frame structure.
- 10 2. In a burial casket, a body section, a cover for said body including two sections, one being an open frame structure hinged

to the body section, the other a lid hinged to the frame structure, means for maintaining the frame structure in a vertical position 15 and the lid in an angular position to the body section, a support pivotally mounted within the frame structure, an incandescent lamp carried by said support, and means operating to maintain said support in ad- 20 justed angular positions relative to said frame structure.

In testimony whereof I affix my signature.
JAMES N. McCONNELL.
